CROSSING SIGNAL

Mercer D. Wilson, Phoenix, Ariz.

Application August 17, 1935, Serial No. 36,710

11 Claims. (Cl. 246—130)

My invention relates to traffic signals, particularly to automatic signal mechanisms for railroad crossings, and is directed to an improvement based on the device shown in my Patent Number 1,890,352, issued December 6, 1932, entitled "Crossing signals," and the disclosure of my co-pending application, serially numbered 11,597, filed March 18, 1935, entitled "Crossing signal."

The present invention embodies the same general principles as those disclosed in the aforesaid patent and patent application. The signal means adapted to control traffic across a railroad track reciprocates between a "stop" position and a "go" or clear position, one movement of the reciprocation being effected by a power-driven mechanism and the opposite movement being accomplished by gravity. By this arrangement, the power-driven movement not only moves the signal member from one position to another, but also, by displacing a suitable weight against the force of gravity, stores energy in the form of energy of position to be used in accomplishing the opposite movement of the signal member.

Preferably the signal member indicates "go" when it is at the end of the power-driven movement, energy then being stored for the opposite movement of the signal member to the "stop" position. In other words, when the signal is in the clear position potential energy is available for the signal movement, and an approaching train or control vehicle merely releases the stored energy. After the departure of the train, the reverse power-driven movement is automatically initiated and completed to place the parts of the signal mechanism in their normal "go" position. The word normal, as hereinafter used, will refer to the position of the mechanism at the "go" or clear position of the signal.

An important advantage of this arrangement is that, if the power-driven mechanism fails, the signal member will subsequently fail to move from the "stop" position when the train clears the controlled zone, thereby calling attention to the condition of the mechanism before any serious accident can be caused by the breakdown.

An additional safety feature is that the signal is maintained in the "go" position only so long as an electric control circuit is energized. Consequently, whenever the control circuit fails, or is broken by accident, the signal member will immediately move to the "stop" position, regardless of the proximity of a train, thereby calling attention to the need for immediate repair. As in my previous disclosures, I prefer that the power-

driven mechanism comprise a hydraulic lift actuated by an electrically driven pump.

Important objects of my invention include the provisions of a new cam arrangement and an improved form of weight, whereby the cost of manufacturing the device will be lowered and the amount of energy-expenditure and expense to operate the signal will be substantially reduced. These and other objects and advantages of my invention will be apparent in the following detailed description.

In its broadest aspect my improvement comprises a signal-actuating shaft in combination with two cam means operatively associated with the shaft and adapted, respectively, to rotate the shaft in opposite directions, together with means to cause relative movement between said cam means.

In the accompanying drawings—

Fig. 2 is an enlarged side elevation with the outer housing or casing shown in section;

Fig. 3 is a vertical, medial section of Fig. 2;

Fig. 4 is a fragmentary vertical section taken as indicated by line 4—4 of Fig. 3; 25

Fig. 5 is a side elevation of a portion of the device, with the casing shown in section to reveal the latch mechanism in the normal position;

Fig. 6 is a view similar to Fig. 5, showing the latch mechanism in an alternate position; 30

Fig. 7 is a horizontal section taken as indicated by line 7—7 of Fig. 5, showing the mechanism in the normal latched position;

Fig. 8 is a horizontal section of the signal mechanism, taken as indicated by the line 8—8 of Fig. 6; 35

Fig. 9 is a vertical section, taken as indicated by 9—9 of Fig. 8;

Fig. 10 is a vertical section, taken as indicated by the line 10—10 of Fig. 9, with the signal mechanism in the "stop" position;

Fig. 11 is a vertical section taken as indicated by line 11—11 of Fig. 8, with the signal in the "stop" position;

Fig. 12 is a wiring diagram, indicating one of the electrical arrangements that may be utilized in my invention;

Fig. 13 is a developed schematic drawing to indicate the relative positions of the two cams at the "go" position of the signal; 45

Fig. 14 is a similar drawing indicating the relative positions of the cams at the "stop" position;

The mechanism of the signal is housed in a cylindrical casing 20, having a conical top 21. The base plate 22 of the casing is integral with 55

a platform 23 that supports the major part of the mechanism. This mechanism includes a hydraulic cylinder 24, having a vertically extended cylinder head 25.

5 The signal member utilized may be in the form of a barrier, generally designated by numeral 26, carried by a horizontally extending arm 27, the arm being rigidly mounted to a floating, vertical signal shaft 28. Preferably, barrier 26 is counterbalanced by a suitable weight 29 carried by an arm 30 mounted on shaft 28 diametrically opposite from arm 27. A cable 31 braces arm 27, and a second cable 32 braces arm 30, as shown.

Floating shaft 28 is slidably journaled in two bearings, one bearing 33 being built into conical top 21, the other bearing 34 being incorporated in cylinder head 25. For weather protection, shaft 28 may be provided with a conical hood 35 extending over the top of the casing in spaced relation thereto, the hood having a depending annular portion 36.

Shaft 28 is supported by two rollers, or cam-followers 37 mounted on a pair of stub shafts 39 that extend diametrically from signal shaft 28. 25 These rollers are positioned to rest in turn on either or both of two cooperating arcuate cams concentric with the shaft, these being a stationary cam 40 and a movable cam 41. I prefer to split each of these rollers into two units, one 30 for each cam, as shown.

Stationary cam 40 is of cylindrical configuration, and is enlarged at the lower end to engage and rest upon cylinder-head 25, suitable screws 35 40a being employed for assembly. The cylindrical body of the cam is provided with two longitudinal slots 42 positioned diametrically from each other. The upper edge of the cylindrical body provides an arcuate cam having two diametrically disposed low points 43 and 44 and, alternating therewith, two diametrically disposed high points 45 and 46 as may be understood by referring to Figs. 13 and 14. The shape shown provides two normally effective diametrically disposed cam surfaces 47 inclined in one circumferential direction, and two diametrically disposed cam surfaces 48 of opposite inclination.

Movable cam 41, likewise of cylindrical configuration, slidably embraces stationary cam 40. 50 The top edge of movable cam 41 is divided into two effective cam surfaces 59, both of which are inclined in the opposite circumferential direction from the aforementioned effective surfaces 47 of the fixed cam. It will be noted that low points 51 of movable cam 41 are positioned in staggered relation to low points 43 and 44 of the stationary cam, i. e., the low points of the movable cam are closer to the high points of the stationary cam than to the low points of the 55 stationary cam.

To prevent cam-followers 37 from passing over the high points 45 and 46 of the stationary cam, suitable stops may be provided on either cam. In the drawings the stops comprise fingers 52 60 integral with movable cam 41.

Movable cam 41 is mounted on a suitable plate 53, and is prevented from rotating by virtue of end portions 54 of the plate extending through aforementioned slots 42 of the fixed cam. Plate 70 53 is centrally apertured to surround signal-shaft 28, in spaced relation. The mass of movable cam 41, together with plate 53, is such that the cam will gravitate downward freely and in a positive manner.

75 When the preferred form of my device is in

operation, signal-shaft 28 is normally held in a first signal position by latch means that will be described later, the movable cam being latched in its elevated position with the cam-followers at the upper ends of inclined cam surfaces 47 5 of fixed cam 40.

When the signal moves from its normal "go" position to the "stop" position, cam 41 gravitates downward, rollers 37 following down inclined surfaces 47, thereby rotating the signal-shaft 90 10 degrees to place barrier 26 across the traffic lane to be controlled. If the progress of the signal barrier towards the "stop" position is impeded by some obstacle, such as a vehicle in the traffic lane, the rollers will be delayed on cam surfaces 15 47, and, upon removal of the obstacle, will continue towards the "stop" position.

If, while in the "stop" position, barrier 26 is struck from the front, rollers or cam-followers 37 will be forced up cam surfaces 47; and if the signal barrier is struck from the opposite side, rollers 37 will pass up either cam surfaces 48 of the stationary cam or cam surfaces 50 of the movable cam, whichever of these cam surfaces is the higher. In either situation, fingers 52 will prevent the signal passing over high points 45 and 46 of the stationary cam, and, in either situation, inclined surfaces will cause the signal to gravitate to the desired "stop" position.

The power means in the preferred form of my 30 invention for moving cam 41 upward includes a hydraulic lift.

In the construction shown in the drawings, hydraulic cylinder 24 embraces a suitable piston 56, 35 from which two spaced piston rods 57 extend upward through piston-head 25, terminating in plate 53.

To limit the upward movement of the piston under hydraulic action, the piston may be provided with a suitable relief valve 58, that normally 40 covers relief passages 59. The valve includes a stem 60, extending upward a suitable distance towards cylinder-head 25. The valve is normally maintained in a closed position by virtue of a suitable helical spring 61 confined between piston 56 45 and a stop 62 on stem 60.

It may be noted here that in the construction shown, the piston reciprocates only over the lower portion of cylinder 24. The pump, generally designated by numeral 63, is mounted below the cylinder in the space between platform 23 and base plate 22. The pump may be of the gear type, comprising two interlocking rotary elements 64 and 65, in pump chamber 66. The two rotary elements are mounted, respectively, on shafts 67 55 and 68, shaft 68 being driven by a suitable motor 69.

Any fluid may be used in the hydraulic lift, preferably a suitable grade of oil. The space in cylinder 24, above the piston, is utilized as a reservoir, the oil being pumped out of the reservoir into the cylinder under the piston to raise the movable cam, and being returned to the reservoir when the movable cam forces the piston down. The drawings show an arrangement that may be 65 employed to provide such a cycle of fluid movements.

From a port 70 in the cylinder wall just above the upper position of piston 56 (Fig. 11), a down-flow passage 71 (Fig. 10), leads to pump chamber 70 66. From the outlet side of the pump a pressure passage 72 leads to the bottom of a vertically disposed valve chamber 73, in which a valve 74 is free to move longitudinally from a normal lower position, shown in Fig. 10, to an alternate higher 75

position, the valve moving upward by fluid pressure from the bottom. The valve includes an extensive stem 75, terminating in a valve head 76. Preferably, the gravitational return of the valve 5 is facilitated by a helical spring 77, confined between valve head 76 and the upper end wall 78 of the valve chamber. End wall 78 has a suitable bleeder port 79 to provide ready escape of any fluid trapped above the valve head.

10 When the valve is in its uppermost position, it clears a lower valve port 80, from which a passage 81 leads to port 82 in the cylinder wall below the lowermost position of piston 56. In such position of the valve, an upper valve port 83 is cut 15 off from both pump pressure passage 72 and lower cylinder passage 81. In the lowermost position of the valve (Fig. 10), pressure passage 72 is cut off, and communication is established between the space in the cylinder under piston 56 and the 20 space in the cylinder above piston 56, as follows: port 82, lower cylinder passage 81, port 80, valve chamber 73, upper valve port 83, up-flow passage 84, and spaced ports 85 and 86 in the cylinder wall above the uppermost position of the piston. It 25 will be noted that the arrangement is equivalent to an ordinary three-way valve responsive to fluid pressure, i. e., when a pump is in operation fluid pressure forces the valve to its uppermost position, thereby placing the pump in communication 30 with the cylinder under the piston, and when the pump ceases operation the valve automatically returns to a position placing the lowermost portion of the cylinder in communication with the uppermost portion of the cylinder.

35 Since oil trapped in pump pressure passage 72 may hinder, if not prevent, the downward return of valve member 74, either the pump must permit sufficient reverse leakage to release the trapped oil, or a suitably dimensioned bleeder passage 87 40 must be provided between pressure passage 72 and down-flow passage 71.

Normally, the movable cam is held at its uppermost position, independent of the hydraulic lift by virtue of a latch means to be described 45 later. When a train or control vehicle enters the control zone of the track, the movable cam is released to gravitate downward, thereby turning the signal to the "stop" position, and forcing oil from the bottom of the cylinder to the top 50 of the cylinder through passage 84. Relatively fast movement of the signal barrier for the first 30 degrees of rotation, and slower movement for the remaining 60 degrees, may be accomplished 55 by controlling the flow of fluid through passage 84, in accordance with the desired rate of movement of the signal.

For this purpose, the upper portion of passage 84 is enlarged to a time-control cylinder 88, in which reciprocates a time-control plunger 89. 60 By means of a connecting rod 90, extending upward through a suitable packing gland 91, time-control plunger 89 is connected to a bracket 92, the bracket being secured to movable cam 41 by screws 92a (Fig. 4).

65 Plunger 89 has one or more longitudinal passages 93, dimensioned to suitably restrain the flow of oil through up-flow passage 84. Preferably, adjustment of degree of restraint of oil-flow is provided by a complementary disk 94, 70 having suitable apertures corresponding to passages 93 in the time-control plunger. This disk may be held fixed by a nut 95 in any of various positions partially closing passages 93.

The reasons for providing two ports 85 and 86, 75 spaced as shown, will now be apparent. In the

normal position of the signal, time-control plunger 89 clears lowermost port 85 by a distance corresponding to the first 30 degrees of the signal movement. When the movable cam is released to gravitate downward, the time-control plunger 5 will not restrict the flow of fluid through passage 84 until it begins to cut off port 85. Thereafter, however, the downward movement of the cam will be retarded by the restricted flow of the oil through apertures 93, until the time-control piston reaches its lowermost position indicated in Fig. 10. Two spaced ports are required so that when the time-control plunger is passing over lowermost port 85, uppermost port 86 will be available for oil passage. 10

15 The latch means to hold signal shaft 28 in the normal first signal position may be associated either with the shaft directly or with movable cam 41. In my preferred form of the invention set forth in the drawings, two latches are employed: one associated with the shaft, and the other effective to hold up the movable cam independently. If the latch associated with the shaft should fail, obviously the device will still function by virtue of the latch associated with the movable cam. If the latter latch should fail the first latch would suffice to hold the signal member at the normal first position, but, desirable control of the speed of rotation of the shaft to the second signal position will be lacking. 30

A rack member 96 assembled to fixed cam 40 and cylinder head 25 by suitable bolts 97 is curved concentric to shaft 28. The upper edge of this member is formed as a spiral rack 98, corresponding to an effective cam surface 47 on fixed cam 35 40, and a longitudinal edge of the member is formed as a vertical rack 99.

A latch member generally designated by numeral 100 to releasably hold signal shaft 28 at the normal first position is rotatably mounted on one of stub shafts 39 and secured thereto by a suitable screw 101. This latch member comprises a rotary latch member 102, having a latch tooth 103, and a pinion 104 fixed to said rotary member and adapted to mesh with spiral 45 rack 98. A second latch member generally designated by numeral 105 to releasably hold movable cam 41 at its elevated position, is rotatably mounted on a stub shaft 106 extending radially from movable cam 41, the latch member being 50 secured to the shaft by a suitable screw 107. This second latch member is similar to the first, comprising a rotary latch member 108, having latch tooth 109, and a pinion 110 fixed to said rotary member in a position to mesh with vertical rack 55 99.

A shelf 111, having a central aperture 112 to clear signal shaft 28, extends diametrically across casing 20, resting at its ends on an inwardly extending flange 113 integral with the casing wall. 60 The shelf may have a depending arcuate flange 114 near each end position to abut said casing flange 113. Preferably, a pair of rods 111a extend upward from platform 23 to shelf 111, as shown.

Mounted on the lower side of shelf 111 is a latch bracket 115, having a lateral arm 116 integral therewith. Arm 116 is vertically apertured to slidably embrace and guide a longitudinal movable latch-release 117. Latch-release 117 is a bar provided with laterally extending pins 118 and 119, and has a reduced lower end bent to form a finger 120. Finger 120 extends laterally into a vertical slot 121 in a latch weight 122. 70

Mounted on the lower end of latch bracket 115 is a suitable motor cut-off switch 123, operated by a plunger 124, the plunger being fixed to a bracket 125 attached to latch weight 122. This switch is closed when the plunger is down (Fig. 6), and is open when the plunger is up (Fig. 5).

Journalized in standard 115 are two arbors 126 and 127. Keyed to the inner end of arbor 126 is a pawl 128, positioned to engage latch tooth 103; and keyed to the outer end of the arbor is a latch arm 129 having a large slot 130 to receive pin 118 on latch-release 117. Keyed to the inner end of arbor 127 is a second pawl 131 positioned to engage latch tooth 109; and keyed to the outer end of arbor 127 is a latch arm 132 having a slot 133 to receive lower pin 119 of latch release 117. Both pawls 128 and 131 are relatively heavy to overbalance their respective latch arms 118 and 119.

20 In the normal positions of the various parts of the latch mechanism shown in Fig. 5, latch weight 122 is held at its uppermost position by virtue of electro-magnetic coupling between an armature 134 integral with the top end of the weight, and an electro-magnet 135 mounted on the under side of shelf 111. The electro-magnet shown is U-shaped, with a coil 136 around one leg. By virtue of the fact that finger 120 rests against the lower end of slot 121 in the latch weight, latch-release 117 is held at an elevated position that permits pawls 128 and 131 to rest in engagement with their respective latch teeth.

When the electro-magnet is de-energized by a train entering the control zone of the track, latch weight 122 is released to gravitate downward. Slot 121 is of sufficient length to provide a substantial degree of lost motion between latch weight 122 and finger 120, with the result that the released weight strikes the finger with sufficient force to jar pawls 128 and 131 from their latched positions. As long as a train is in the control zone, weight 122 will remain suspended from finger 120 in the position shown in Fig. 6.

While electro-magnet 135 is of sufficient strength to hold the latch weight suspended in the position shown in Fig. 5, it is not of sufficient strength to draw the weight upward against gravity from the position shown in Fig. 6. I have, therefore, provided automatic means for restoring the latch weight to its normal position upon the arrival of movable cam 41 at its uppermost position.

Below the weight, a vertically disposed cut-off cylinder 139 communicates with main cylinder 24 by an upper passage 140 and a lower passage 141, lower passage 141 opening to a chamber 142 on the wall of main cylinder 24. Towards the upper end of chamber 142 a bore, or group of bores, generally designated by numeral 143, extends through the wall of cylinder 24, and a similar bore, or group of bores, generally designated by numeral 144, extends through the wall of the main cylinder near the lower end of chamber 142.

A suitable cut-off plunger 145, slidably mounted in cut-off cylinder 139, is mounted on a rod 146. The rod extends upward through a packing gland 147 into a vertical bore 148, in weight 122. A suitable helical spring 149 embraces rod 146 below weight 122, the spring resting upon a suitable sleeve 150 adjustably mounted on the rod.

Normally, i. e., when the signal is in the clear position and no train is in the control zone of the track, rod 146 rests upon a bottom end plate 75 151, holding cut-off plunger 145 at a position just

above passage 141, and no effective pressure is exerted by spring 149 against the bottom of latch weight 122.

When latch weight 122 is released by a train entering the control zone, it may fall far enough to contract spring 149, partially as shown in Fig. 6. As soon as the train clears the control zone, motor 69 is energized and pump 63 begins to deliver oil to the bottom of cylinder 24 beneath piston 56. When piston 56, on its upward movement, opens the lowermost of bores 144, oil under pressure escapes into chamber 142 and passage 141 to exert pressure on the under side of cut-off plunger 145. The full force of the oil pump is not delivered against the cut-off plunger initially, however, because bores 143 and bores 144 are so spaced that momentarily oil flows both outward from underneath the piston through one or more of bores 144 and inward above the piston through one or more of bores 143. This momentary condition ceases as piston 56 moves upward to completely cover bores 143, and to completely uncover all of bores 144, so that the full force of the pump is thereafter delivered against cut-off plunger 145.

20 The cut-off plunger is forced upward, carrying with it rod 146, the upward movement forcing weight 122 into the normal position shown in Fig. 5. It will be noted that spring 149 serves as a shock-absorber and permits a certain latitude in the adjustment of sleeve 150.

If, for any reason, motor cut-off switch 123 is not closed by the arrangement described to stop the pump, damage to the mechanism will be prevented by the action of relief valve 58, as previously described.

As soon as pump 63 stops, cut-off plunger 145 returns to its normal position at the lower end of its range of reciprocation, and latch weight 122, except for the attraction of electro-magnet 135, 40 is again free to drop down upon finger 120. It is contemplated that all pressure in cylinder 24 beneath the piston, will be released immediately after the pump stops, by virtue of valve 74 returning to its lowermost position and thereby 45 providing free communication from port 82 at the bottom of the cylinder to ports 85 and 86 at the top of the cylinder.

An electrical arrangement that may be employed to operate the signal includes two control 50 switches, both of which must be closed to energize the signal motor, one being a mechanically operated switch that opens only when the signal is in the "go" position, the other being an electrically operated switch open only when a train 55 is in the control zone. Both switches in such an arrangement will be closed to operate the motor whenever the signal is in the "stop" position and no train is in the control zone. Of these two switches, the mechanically operated switch is 60 motor cut-off switch 123 described above.

A wiring diagram showing the essential features of such an electrical arrangement is shown in Fig. 12. Relay 152 is normally energized in a closed position by wires 133 and 134 that are part 65 of a circuit associated with the control zone of the railroad track. Whenever a train enters the control zone this circuit is short-circuited to de-energize relay 152, thereby breaking the normal circuit through electro-magnet 135. This last 70 normal circuit includes wire 155, battery 156, wire 157, relay member 158, and wire 159 to the other side of the electro-magnet.

When the electro-magnet releases weight 160 of the wiring diagram, which represents latch 75

weight 122 in the device itself, a switch member 160a connects contacts 161 and 162, the switch member and two contacts representing cut-off switch 123 previously described. The dropping 5 of switch member 160a against contacts 161 and 162 does not, however, close motor relay 163 because the circuit required to do so includes relay member 158. When, however, the train leaves the control zone and relay 152 automatically closes, 10 motor relay 163 is energized through the following circuit; battery 156, wire 157, relay member 158, wire 159, wire 164, switch member 160a, wire 165, coil of relay 163, wire 166, and wire 155 back to battery 156. When relay 163 is thereby 15 energized, the following motor circuit is established: battery 156, wire 157, wire 167, relay member 168, wire 169, motor 69 and wire 155 back to battery 156.

The operation of my invention may be readily 20 understood from the foregoing description. When the various parts are in their normal positions, with the control zone of the track clear, relay 152 is closed; electro-magnet 135 is energized; cut-off switch 123 is open; the signal is 25 in the "go" position; movable cam 41 and piston 56 are held at their uppermost positions by the lowermost of the two latches; the signal shaft is held at its normal position by the uppermost 30 of the two latches; latch weight 122 is held at its highest position by electro-magnet 116; cut-off plunger 145 rests at its lowermost position; and, since the motor and pump are idle, valve 74 is at its lowermost position, providing free 35 communication between the portion of the cylinder below the piston and the portion of the cylinder above the piston.

As soon as a train enters the control zone, thereby de-energizing the track relay, electro-magnet 135 is de-energized, releasing latch 40 weight 122. The latch weight drops with suitable impact against finger 126, thereby disengaging both latches with a jerk, and at the same time closing motor cut-off switch 123. Latch pawls 128 and 131 are then held in suspended position 45 by pins 118 and 119, respectively, as shown in Fig. 6. Pinion 104 being free to rotate, moves downward around rack 99 as the two cam-followers gravitate down cam surfaces 47 of stationary cam 40. Pinion 110 also being free to rotate, 50 moves down rack 99 as the movable cam gravitates downward. The downward movement of the cam-followers is governed by the oil-controlled downward movement of cam 41. The signal swings rapidly 30 degrees until time-control 55 plunger 89 becomes effective, and then proceeds more slowly the remaining 60 degrees to the "stop" position.

As soon as the control zone of the track is again clear, the motor circuit is re-established, as 60 heretofore described, and pump 63 begins to deliver oil through the cylinder under piston 56, valve 74 being moved to its upper position automatically. The pump continues to force piston 56 and movable cam 41 upward to permit pawls 65 128 and 131 to drop into position for engagement with their respective latch teeth, and then to close cut-off switch 123.

For the purpose of completely disclosing my 70 invention and illustrating the principles involved, I have restricted my description to the preferred form of my invention; but the principles involved may be embodied in other forms, and I, therefore, reserve the right to all changes and modifications that properly come within 75 the scope of my appended claims.

Having described my invention, I claim:

1. A signal having in combination: a signal member; a vertical floating shaft operatively connected with the signal member; an arcuate cam adjacent the shaft, having a cam surface 5 sloping downward in one circumferential direction to a lowest level, a second arcuate cam adjacent the shaft having a cam surface sloping downward in the opposite circumferential direction to a lowest point, said two lowest points being staggered; a cam-follower associated with the shaft to support the shaft on either or both said cams; and means to cause relative axial movement of said cams to rotate the shaft in alternate directions.

2. A signal of the class described, having in combination: a signal member; a floating vertical shaft operatively connected with the signal member; a stationary arcuate cam concentric to the shaft having a cam surface inclining downward in one circumferential direction; a second arcuate cam concentric to the shaft having a cam surface inclining downward in the opposite circumferential direction, said second 10 cam being movable vertically; a cam-follower 15 radially mounted upon the shaft to support the shaft upon either or both of said cam surfaces; and means to raise the second cam to rotate the shaft in one direction and vice versa.

3. A signal of the class described, having in combination: a signal member; a floating vertical shaft operatively connected with the signal member; a stationary arcuate cam concentric to the shaft having a cam surface inclining downward in one circumferential direction; a second arcuate cam concentric to the shaft having a cam surface inclining downward in the opposite circumferential direction, said second cam being movable vertically; a cam-follower 20 radially mounted upon the shaft to support the shaft upon either or both of said cam surfaces; and means to raise the second cam to rotate the shaft in one direction and vice versa.

4. A signal having in combination: a vertical longitudinally movable shaft; a signal member operatively connected to the shaft; a cam-follower mounted on the shaft; a stationary cam adapted to cooperate with the follower to support the shaft, said cam having an inclined cam surface to cause the shaft to gravitate from a normal first signal position to a second signal 50 position; latch means responsive to the approach of a control vehicle to releasably retain the follower at the normal first position; and a power-driven cam adapted to be energized upon departure of the control vehicle to force the follower up 55 said inclined surface to the normal latched position.

5. A signal having in combination: a signal member; a floating vertical shaft operatively connected with the signal member; a stationary 60 arcuate cam concentric to the shaft having a cam surface inclining downward in one circumferential direction; a second axially movable arcuate cam concentric to the shaft having a cam surface inclining downward in the opposite 65 circumferential direction; a cam-follower associated with the shaft to support the shaft on either or both said cams; power actuated means to raise the second cam, thereby causing the shaft 70 to rotate in one direction, said second cam being 75

adapted to gravitate downward from its raised position thereby permitting the stationary cam to rotate the shaft in the opposite direction; and latch means responsive to a passing vehicle to releasably retain the shaft at the position resulting from the upward movement of said movable cam.

6. A signal having in combination: a signal member; a floating vertical shaft operatively connected with the signal member; a follower mounted on the shaft; a stationary cam in position to support the follower and thereby the shaft, said cam having cam surfaces inclined in one direction whereby the shaft will rotate by gravitation from a first signal position to a second signal position; a second cam having a cam surface inclined in the opposite direction, said second cam being adapted when moved upward to engage the follower, thereby rotating the shaft in the reverse direction from the second signal position to the first signal position, said cam being adapted to gravitate from its raised position; a latch means to releasably hold the signal shaft at its first position, said latch means being adapted to release the signal shaft in response to the approach of a control vehicle; and power means adapted to be energized upon departure of the control vehicle to raise said second cam.

7. A signal having, in combination: a signal member; a floating vertical shaft operatively connected with the signal member; a follower mounted on the shaft; a stationary cam in position to support the follower and shaft, said cam having cam surfaces inclined in one direction whereby the shaft will rotate by gravitation from a first signal position to a second signal position; a second cam having a cam surface inclined in the opposite direction, said second cam being adapted when moved upward to engage the follower, thereby rotating the shaft in the reverse direction from the second signal position to the first signal position, said cam being adapted to gravitate from its raised position; a latch means to releasably hold the follower at its first position; a second latch means adapted to releasably hold the second cam at its raised position, both of said latch means being adapted to be released in response to the approach of a control vehicle; and power means adapted to be energized upon departure of the control vehicle to raise said second cam.

8. A signal having in combination: a signal member; a floating vertical shaft operatively connected with the signal member; a follower mounted on the shaft; a stationary cam in posi-

tion to support the follower and shaft, said cam having a cam surface inclined in one direction whereby the shaft will rotate by gravitation from a first signal position to a second signal position; a second cam having a cam surface inclined in the opposite direction, said second cam being adapted when moved upward to engage the follower, thereby rotating the shaft in the reverse direction from the second signal position to the first signal position, said cam being adapted to gravitate from its raised position; a latch means to releasably hold the follower at its second position; a second latch means adapted to releasably hold the second cam at a raised position free from the latched follower, both of said latch means being adapted to be released in response to the approach of a control vehicle.

9. A signal having in combination: a signal member; a vertical shaft operatively connected to the signal member; two arcuate cams adapted respectively to rotate the shaft in opposite directions; a follower connected to the vertical shaft and partially supporting the shaft on each said cams; and means to cause axial movement of one of said cam means relative to the other whereby said cam means will be alternately effective to rotate the shaft.

10. A signal having in combination: a signal member; a vertical shaft operatively connected to the signal member; a cam inclined to rotate the shaft in one direction; a second cam inclined to rotate the shaft in the opposite direction, said two cams being disposed to form a valley; a cam-follower operatively connected with the shaft and resting in said valley; and means to cause relative movement between the two cams, thereby causing the vertex of the valley to shift for the purpose of rotating the shaft.

11. A signal having in combination: a signal member; a vertical shaft operatively connected with the signal member; a pair of diametrically-disposed followers extending radially from the shaft; an arcuate cam concentric to the shaft having two cam surfaces sloping in one circumferential direction; a second cam concentric to the shaft having two cam surfaces sloping in the opposite circumferential direction, said cam surfaces being disposed to form two diametrically-opposite valleys to support said cam-followers; and means to cause relative axial movement between the two cams, thereby causing the low points of said valleys to shift for the purpose of rotating said shaft.
